UNITED STATES PATENT OFFICE.

GARFIELD P. LENNARTZ AND ANTON A. SCHUMACKER, OF CHICAGO, ILLINOIS.

FOLDING BED.

Application filed September 26, 1922. Serial No. 590,596.

To all whom it may concern:

Be it known that we, GARFIELD P. LENNARTZ and ANTON A. SCHUMACKER, citizens of the United States, residing at Chicago, in the county of Cook and State of Illinois, have invented certain new and useful Improvements in Folding Beds, of which the following is a specification.

While the present invention is particularly adapted for use in connection with automobiles and is intended to provide a convenient camping kit, it may also be utilized for general purposes and embodies a combined luggage carrier, table, and folding bed.

The principal object of this invention is to provide a device which may be readily attached to an automobile running board for holding luggage and which may be manipulated to provide a table and also a bed. Other objects are to provide a device of this character which is simple in construction and which will be substantial and durable in operation; to provide a luggage carrier having either a canvas or spring bed which will form the bed bottom when the carrier is unfolded and which has an outer plate adapted to serve as a support for the bed and which may also be utilized as a table; and in general to provide such improved apparatus as will be described more fully hereinafter and which is shown in the accompanying drawings, in which;

Figure 1 is an end view showing the device in position on the running board;

Figure 2 is a side view taken from the right hand side of Figure 1 with parts broken away or shown in section;

Figure 3 is an end view showing the device arranged as a bed and also showing the device in dotted lines as arranged for a table;

Figure 4 is a sectional detail taken on the line 4—4 of Figure 1;

Figure 5 is a section taken on the line 5—5 of Figure 1;

Figure 6 is a section taken on the line 6—6 of Figure 1;

Figure 7 is a plan view of the locking device for the telescoping rails;

Figure 8 is an end view similar to Fig-

ure 3 showing the device provided with bed springs or a spring bottom;

Figures 9 and 10 are details showing auxiliary supporting legs; and

Figure 11 is a section taken on the line 11—11 of Figure 10.

In the particular arrangement shown in these drawings, two U-shaped clamps or supports 10 are provided for engagement with the running board 11. Each of these clamps has one or more clamping screws 12 and 13 for fastening it to the board. Two angles or rails 14 are pivoted to the inner ends of the clamps at 15. These angles are provided at their outer ends with clips 16 for engagement with similar telescoping angles or bars 17 which engage with the angles 14. The angles 17 also have similar clips 18 at their inner ends for engagement with the angles 14 to complete the telescoping joints. These parts are made telescoping in order to give sufficient length for the rails when used as a bed and yet not having the parts project upwardly too far when used as a luggage carrier. Tongues 19 are secured to the bars 17 and are provided with pins 20 for engagement with holes 21 in the bars 14 in order to hold the parts in extended position as shown in Figures 3 and 7. The upper ends of the angles 17 are bent outwardly to form cross bars or hinged arms 22 which are hinged at 23 to the correspondingly inward bent arms 24 of the outer members or angles 25. When the device is arranged as a luggage carrier, the lower ends of these angles engage with hooks 26 on the brackets 10 as shown in Figure 1. They are further held in this position by means of latches 27 which are pivoted at 28 to the brackets 10 and engage with catches 29 on the angles 25 as shown in Figures 1 and 6. The lower ends of the angles 25 are connected by a cross bar or angle 30 which may be formed integrally therewith.

The table 31 has an angle iron frame comprising end pieces 32 and an integrally formed cross piece 33 which support the table top or plate 34. The lower ends of the end pieces are offset and are pivoted

at 35 to the angles 25, the arrangement being such that the table may swing freely between these angles or end members. Two arms 36 are pivoted to the table at 37 and 5 are hinged at their outer ends 38 to similar arms 39 which are pivoted at 40 to the angles 25. These provide folding supports or braces for the table when it is swung outwardly as shown in Figure 3. They 10 also serve to lock or support the table in raised position as shown in Figure 1 and when in this position provide end pieces for the luggage carrier. They also serve as braces for the table when it is swung 15 downwardly to provide a leg or support for the bed as shown in full lines in Figure 3.

A center support 41 is also provided for holding the bed. This support comprises 20 two side bars or legs 42 which are connected at the bottom by a cross piece 43 and are pivoted at 44 to the arms 22. This support is also preferably braced by means of cross braces 45 which also serve as inner cross 25 pieces for the luggage carrier. Legs or braces 46 are pivoted at 47 to the legs 42 and at 48 to the angles 25 as shown in Figures 1 and 3. These legs or braces not only help to hold the support 41 in position but also 30 provide additional end pieces for the luggage carrier.

A roller 49 is mounted in brackets 50 on the angles 14 and carries a sheet or strip 51 of canvas, duck or other suitable material 35 for forming a bed bottom. A ratchet wheel 52 is connected to the roller 49 and is adapted to be engaged by a pawl 53 for holding the roller in adjusted position. The roller may be turned by means of a detachable 40 wrench 54. The outer or free end of the strip 51 is secured to a wooden bar 55 which has a number of hooks 56 for fastening the outer end in position. When the device is 45 adjusted for use as a luggage carrier these hooks are engaged with the upper end of the table and the canvas 51 is brought down to the outer side of the carrier as shown in Figure 1 and then across the bottom so as to make a support and protection for whatever luggage is carried therein. When the 50 device is arranged in this manner, we prefer to have a waterproof covering placed over the carrier as indicated at 57 in Figure 3.

When the device is to be used as a bed, the 55 frame is swung out and the telescoping parts adjusted as shown in Figure 3 and the hooks 56 are engaged with the cross bar 30 at the end of the frame. The bed bottom 51 may then be tightened by turning the roller 49 60 and will be held in adjusted position by the ratchet wheel and pawl.

From this description it will be seen that we provide a combination accessory which may be readily applied to an automobile and 65 which will serve as a substantial luggage

holder or carrier and also provides a table and bed especially adapted for camping purposes. The device occupies but little room and serves to protect the luggage which may be packed therein on the running board.

70

In the modified form of construction shown in Figure 8, a spring bed bottom 58 is provided which has hooks 59 at either end for engagement with the bed frame. The bed bottom is made somewhat shorter than the frame in order to provide proper tension when it is stretched thereover. When this form of bed is to be adjusted, the central portion of the frame is swung upwardly as shown in dotted lines in Figure 8 and the bed bottom hooked over the ends. Then by pressing down on the central portion of the frame, the frame acts as a toggle to tighten the springs, and as the pivot 23 is somewhat below the upper line of the frame the springs 85 tend to hold the parts in proper position as they are pulling beyond the center. It will also be noted that the canvas bed bottom may be adjusted to any desired position and then tightened in the same manner. This 90 toggle action furnishes means whereby a considerable tension may be provided with but little effort.

85

It will be noted that at times it may be desirable to use the bed separately from the 95 automobile, in which case the inner end will need a support to take the place of the running board 11. In order to do this, we provide legs 60 such as shown in Figures 9 and 10, which are pivoted at 61 to the end frame 100 member or rail 62 which connects the side rails 14. These are held in downwardly adjusted position and the frame is supported by means of folding braces 63 which are pivoted at 64 to the legs 60 and are pivoted at 105 65 to brackets 66 on the rails 62. When the device is mounted on the running board, these legs are folded upwardly adjacent to the rails and occupy little or no room. When the device is to be used separately from the 110 automobile, the legs are swung down as shown in Figures 9 and 10 and serve to support this end of the frame, and they also serve to hold the clamps 10 in horizontal position as shown in these figures.

115

It will be noted that various changes may be made in the details of construction and arrangement of the parts in order to adapt the apparatus to different machines or for different conditions and therefore we do not 120 wish to be limited to the exact construction herein shown and described, except as pointed out in the following claims, in which we claim:

1. A device of the character set forth, 125 comprising a frame formed of inner and outer folding sections and adapted to be secured to a running board to serve as a luggage carrier, a plate pivoted to the frame and adapted to serve as the outer wall of the 130

carrier and also as a table and as a support for the outer section of the frame when the frame is adjusted to bed form, folding legs which furnish additional support for said frame and a bed bottom adapted to be secured to the frame.

2. The combination with a folding frame adapted to be secured to a running board and folded to vertical position to serve as a 10 baggage carrier and to horizontal position to

serve as a bed, of a table member pivoted to said frame and braces between the table member and frame, said braces serving to hold the table in raised position, in open horizontal position and also when the table 15 is in vertical position serving as a support for the bed, substantially as described.

GARFIELD P. LENNARTZ.
ANTON A. SCHUMACKER.
